UNITED STATES PATENT OFFICE

110,201

DESIGN FOR AN ICE CREAM DIPPER OR SIMILAR ARTICLE

Ernest E. Tutsch, La Crosse, Wis.

Application April 21, 1938, Serial No. 76,679

Term of patent 7 years

To all whom it may concern:

Be it known that I, Ernest E. Tutsch, a citizen of the United States, residing at La Crosse, in the county of La Crosse and State of Wisconsin, have invented a new, original, and ornamental Design for an Ice Cream Dipper or Similar Article, of which the following is a specification, reference being had to the accompanying drawing, forming part thereof.

I claim:—

The ornamental design for an ice cream dipper or similar article, as shown.

ERNEST E. TUTSCH.
